Arnold I. Lorenzen, Toledo, Ohio, assignor to
Owens-Illinois Glass Company, Toledo, Ohio, a
corporation of Ohio

Application May 21, 1952, Serial No. 19,810

Term of patent 14 years

(Cl. D58—8)

To all whom it may concern:

Be it known that I, Arnold I. Lorenzen, a citizen of the United States, residing at Toledo, in the county of Lucas and State of Ohio, have invented a new, original, and ornamental Design for a Bottle, of which the following is a specification, reference being had to the accompanying drawing, forming a part thereof.

Fig. 1 is a side elevational view of a bottle, showing my new design;

Fig. 2 is an end elevational view thereof;

Fig. 3 is a top plan view; and

Fig. 4 is a bottom plan view.

I claim:

The ornamental design for a bottle, substantially as shown.

ARNOLD I. LORENZEN.
